Erwin B. Eising

Attorneys:
Dow, Cushing, & Co.

UNITED STATES PATENT OFFICE.

ALVIN NORRIS, OF MANITOWOC, WISCONSIN.

BUILDING BLOCK.

Application filed April 14, 1924. Serial No. 706,605.

To all whom it may concern:

Be it known that I, ALVIN NORRIS, a citizen of the United States, and resident of Manitowoc, in the county of Manitowoc and 5 State of Wisconsin, have invented certain new and useful Improvements in Building Blocks; and I do hereby declare that the following is a full, clear, and exact description thereof.

10 This invention relates to building blocks. In building blocks as heretofore constructed, there has, in general, been no means for preventing lateral motion. The only bonding between successive blocks has been the 15 mortar, and, therefore, relatively small lateral forces have readily produced cracks in a wall. Attempts at interlocking have been made by using projections, grooves, or similar expedients, but these attempts have 20 resulted in impractical and costly constructions, and in addition, have not resulted in blocks which can be easily handled and which may be relied upon.

This invention is designed to overcome 25 the above noted defects, and objects of such invention are to provide a building block which is free from easily broken projections, which is of the same general size as the ordinary blocks, which may be handled by an 30 unskilled laborer, which will securely bind or lock successive portions of a wall together, and which is so constructed that braced and interlocked corners may be readily formed in a wall.

35 Embodiments of the invention are shown in the accompanying drawing, in which:— Figure 1 is a perspective view of a corner portion of a wall.

Figure 2 is a view of one of the corner 40 blocks.

In building the wall, a plurality of blocks 1 are employed. These blocks, as may be seen, particularly from Figure 1, are formed of two half sections which are of uniform 45 width and have vertical front and rear and end faces. These half sections, however, slope towards each other to form a dihedral angle. In order to adapt these blocks to a smooth flat footing, for instance, a plurality of double wedge shaped blocks 2 are 50 employed and are arranged, as shown in Figure 1, with their narrow edges abutting and with their flat elongated faces in contact with the footing.

55 In the corners it is preferable to employ a single wedge shaped block, as indicated at

3 in Figure 1, and as shown in the left hand side of the corner, to employ a second single wedge shaped block 4. This insures a flat bottom for the wall. Thereafter, the wall is 60 built up by successive tiers of blocks 1. It is to be noted that in alternate tiers, the blocks 1 are inverted so as to secure an overlap and a bonding or tying action between successive blocks. The upper portion of 65 the wall is finished by means of the double wedge shaped blocks 2, as may be seen from Figure 1.

It is to be noted, however, that at the 70 corner, a difficulty arises in the use of the blocks 1, consequently corner blocks are provided, as shown in Figure 2. These corner blocks comprise two half sections one of which, as indicated at 5, slopes downwardly towards one side of the elongated block. 75 The other half section 6 slopes downwardly towards an end of the elongated block. It is to be noted that in Figure 2 an imaginary rectangular solid has been indicated by 80 imaginary lines, so that the slope of the half sections may be easily seen. It is to be noted that the inner upper edge 7 of the half section 6 lies in the same horizontal plane as the side edge 8 of the half section 5. These half sections are of uniform width throughout and triangular shoulders 9 are formed at the plane of union of these half sections.

This figure shows the block turned around with reference to Figure 2. One of these corner blocks is shown in Figure 1. It will 85 be seen that the member or half section 6 accurately conforms to the slope of the blocks 1 in the left hand portion of the wall while the member 5 or half section of the corner block accurately conforms to the slope of the block 1 in the right hand side of the wall. The shoulders 9 securely lock the parts against endwise shifting.

It is to be noted that each alternate tier of the wall uses one of these corner blocks 90 at the corners, one only having been shown in Figure 1.

It will be seen that these building blocks 100 are all of substantially rectangular outline and they are devoid of small readily broken tongues or projecting portions, and are as sturdy and strong as the ordinary building block or brick, and may be handled with the same facility by an unskilled laborer. It is intended that these blocks be made of any 105 desired size. It is to be further noted that the dull monotony of a brick wall is broken 110

by the slanting lines of union between successive blocks when this invention is practised, and consequently an ornamental and attractive wall is provided. It is to be particularly noted that cracks will not form in this wall for the reason that any forces tending to separate portions of the wall are resisted by overlapping interlocking portions of the blocks, whereas, with an ordinary wall, the mortar alone is relied upon.

Although the invention has been described in considerable detail, it is to be understood that the invention may be variously embodied and is, therefore, to be limited only as 15 claimed.

I claim:

1. A building block comprising two parallelepipeds integrally joined and having one vertical edge common throughout its extent, 20 one of said parallelepipeds slanting downwardly towards one side and the other parallelepiped slanting downwardly towards one end of said block, said parallelepipeds having triangular shoulders at their plane 25 of union with the apexes of the triangles at the upper and lower ends of the common vertical edge.

2. A building block having a generally

rectangular shape, said block being formed of two half sections, one of said half sections sloping downwardly towards one side of the block and the other half section sloping downwardly towards one end of said block.

3. A building block having a generally 35 rectangular shape, said block being formed of two half sections of uniform thickness, one of said half sections sloping downwardly towards one side of the block and the other half section sloping downwardly towards one end of said block.

4. A building block having a generally 40 rectangular shape, said block being formed of two half sections of uniform thickness, one of said half sections sloping downwardly 45 towards one side of the block and the other half section sloping downwardly towards one end of said block, said block having triangular shoulders at the plane of union of said half sections.

In testimony that I claim the foregoing I have hereunto set my hand at Manitowoc, in the county of Manitowoc and State of Wisconsin.

ALVIN NORRIS.
